UNITED STATES PATENT OFFICE.

LOUIS H. THULLEN, OF EDGEWOOD, PENNSYLVANIA, ASSIGNOR TO THE UNION SWITCH AND SIGNAL COMPANY, OF SWISSVALE, PENNSYLVANIA, A CORPORATION OF PENNSYLVANIA.

ALTERNATING-CURRENT-TRANSLATING DEVICE.

No. 823,086.

Specification of Letters Patent.

Patented June 12, 1906.

Application filed October 13, 1903. Serial No. 176,836.

To all whom it may concern:

Be it known that I, LOUIS H. THULLEN, a citizen of the United States, and a resident of Edgewood, in the county of Allegheny and 5 State of Pennsylvania, have invented certain new and useful Improvements in Alternating-Current-Translating Devices, of which the following is a specification.

My invention relates to alternating-current-translating devices.

In the drawings I have illustrated my invention in the form of a relay, but it will be understood that it may be applied to any device which is designed to translate alternating-current energy into some other form of energy—for example, mechanical motion.

I will describe an alternating-current-translating device in the form of a relay embodying my invention and then point out the 20 novel features thereof in claims.

In the accompanying drawings, Figure 1 is a side elevation of an alternating-current relay embodying my invention. Fig. 2 is a horizontal sectional view of the relay shown in 25 Fig. 1, the section being taken on the line 2 2 and looking in the direction of the arrow. Fig. 3 is a view partly in elevation and partly in vertical section, the section being taken on the line 3 3 of Fig. 2. Fig. 4 is a similar view 30 taken on the line 4 4 of Fig. 2. Fig. 5 is a detail sectional view. Figs. 6, 7, and 8 are each detail views of parts comprised in the relay of Figs. 1 to 5.

Similar letters of reference designate corresponding parts in all of the figures.

The mechanism or parts comprised in the relay are inclosed in a suitable casing consisting of a top plate a , a bottom plate a' , and a wall a'' . The wall a'' is preferably of some 40 transparent material—for example, glass. The several parts of the casing are secured together by means of bolts a^3 .

The relay comprises a core, an energizing coil or coils, and a movable part, in effect an 45 armature, which moves in one direction in response to the effects of an alternating current in the coil or coils and moves in a reverse direction in response to gravity or mechanical means when no alternating current is passing 50 through the coil or coils. The reverse movements of the movable members are utilized to make and break contacts included in electric circuits and by such make and breaks to open and close the circuits of said contacts.

B designates a laminated core, which is 55 substantially C-shaped and is suspended from the top plate a by a bracket or brackets b . Each end of the core is split, and around a split portion of each end is placed a metallic band b' of high conductivity. 60

B' B^2 designate two energizing-coils. One coil is provided for each end of the core B, and the two coils are preferably in series. The ends of the core are provided with lateral extensions b^2 b^3 . (See Figs. 6 and 8.) The purpose of these extensions b^2 b^3 is to provide a large area at the poles of the core and reduce the reluctance produced by the air-gap between the ends of the core B to the magnetic circuit of the core. 70

C designates the movable member or armature of the relay, which is made from some non-magnetic material—such, for example, as aluminium. It is shown as being segmental in shape and as being carried by arms c , radiating from a shaft c' . It extends between the ends of the core B, and it is moved, and with it the shaft c' , in one direction by the effects of an alternating current flowing through the coils B' B^2 . Alternating currents flowing through the coils B' B^2 generate lines of force in the core B, which cutting the metal bands b' set up in each of the bands an induced current, which induced currents, however, are of a different phase 85 or are out of step with the current flowing through the coils B' B^2 . The induced currents in the bands b' generate lines of force in those parts of the core which they embrace, and these lines of force generate eddy- 90 currents on the movable member C. The lines of force generated in the core B by the coils B' B^2 , which are displaced with reference to the lines of force generated by the induced currents in the band, also generate 95 eddy-currents on the movable member C. These eddy-currents will be of such polarity and direction relative to the currents in the core B as to cause the member C to rotate with its shaft. The principle involved here- 100 in is substantially the same as the principle involved in most alternating single-phase motors and in some alternating-current-measuring instruments. In order that the maximum effect of the eddy-currents on the 105 movable member be obtained, slots c^2 are provided in the movable member in order that the path of the eddy-currents be length-

ened in parallel paths on the member C rather than in circular paths, which would be the case without the slots. By having these 5 eddy-currents paralleled on the member C they will cut the lines of force produced in the core B by the coils B' B² and bands b' at such angle as to produce the maximum torque on the member C. The shaft c' is preferably a crank-shaft and is journaled at 10 its end on pointed screws c⁵ c⁶, which are adjustable in hangers c⁷ c⁸, depending from the top a. As shown, it is provided with two 15 crank portions c³ c⁴, the purpose of which is to allow the points of contact of the circuit or circuits which the relay is to control to be located close to the center of rotation of the shaft c'. The purpose of having the points 20 of contact close to the center of rotation of the shaft c is that more pressure is obtained in making the contact than would be obtained were the contacts farther away from the center, for the relative distance between the contacts and the center of rotation and the member C and the center of rotation is 25 about the maximum.

The contact-points controlled by the rotation of the member C each comprises a carbon or other point c⁹, which is carried by a binding-post c¹⁰ and a suitable spring contact-plate c¹¹, which plate is suitably fixed on a crank c³ or c⁴ of the shaft. Each contact-spring is electrically connected to one end of a coiled spring c¹². The other end of the coiled spring is electrically connected with a 30 binding-post c¹³. The spring contact-plate c¹¹ is suitably held between insulating-rings c¹⁴, and the coiled spring c¹² is carried by a ring or collar of insulation c¹⁵. c¹⁶ designates binding-posts for the terminals of the coils 35 B' B².

So long as alternating current flows through the coils B' B² the contacts made by the pairs of carbon-points and spring contact-plates will be closed, as the member C will be held elevated (see Fig. 5) by the effect of the 40 alternating current in the manner hereinbefore set forth. When current is cut off from the coils, the member C will rotate downward against a stop c¹⁷; and thus break the 45 contacts.

H designates an adjustable counterweight,

which is provided on the shaft c', the purpose of which is to counterbalance principally the movable member C. By adjusting the counterbalance the relay may be made more or less sensitive of electrical energy traversing the coils. 55

My invention is applicable in all or a part of its features to other alternating-current-translating devices, especially where a part 60 is rotated or partially rotated by reason of a shifting magnetic field produced by alternating currents of different phases.

What I claim as my invention is—

1. In a translating device, the combination 65 of electromagnetic means, a movable member provided with radial slots for lengthening or paralleling the path of eddy-currents produced on said movable member by the electromagnetic means, and contact-points made 70 and broken by the movement of said movable member.

2. In an alternating-current relay, the combination of a movable member operated in one direction by electromagnetic means 75 when affected by an alternating current, and contacts made and broken by the movement of said member, said contacts comprising coiled springs.

3. In an alternating-current relay, the 80 combination with a movable member operated in one direction by electromagnetic means when affected by an alternating current, a crank-shaft upon which said member is supported, and contact-points located near 85 the center of rotation or said shaft.

4. In an alternating-current relay, the combination with a movable member operated in one direction by electromagnetic means when affected by an alternating current, a crank-shaft upon which said member is mounted, contact-points located near the center of rotation of said shaft and spring-plates comprised in said contact-points and carried by said shaft. 90

In testimony whereof I have signed my name to this specification in the presence of two subscribing witnesses.

LOUIS H. THUILLEN
